UNITED STATES PATENT OFFICE.

JAMES S. WHITE, OF CHICAGO, ILLINOIS, ASSIGNOR TO ALLIED GOLF COMPANY, OF CHICAGO, ILLINOIS, A CORPORATION OF ILLINOIS.

GOLF BAG.

1,423,891.

Specification of Letters Patent. Patented July 25, 1922.

Application filed February 21, 1921. Serial No. 446,683.

To all whom it may concern:

Be it known that I, JAMES S. WHITE, a citizen of the United States, residing at Chicago, in the county of Cook and State of Illinois, have invented a new and useful Improvement in Golf Bags, of which the following is a specification.

This invention relates to golf bags and is fully described in the following specification 10 and shown in accompanying drawings in which Figure 1 is a broken perspective view of the golf bag; and Fig. 2 is a section on line 2-2 of Fig. 1.

The golf bag in the embodiment shown 15 consists of bottom about head 10 with a depending flange 11 about which is formed a rawhide bottom member 12. The fabric or other flexible material 13 forming the other side of the bag is placed between the 20 flange 11 and the member 12 and all are secured together as by means of stitching 14.

The top of the bag is formed by bending a strip of rawhide 15 about the top ring 16; between the folds of which is placed the 25 upper end of the fabric 13. The two are then secured together by a suitable means such as the stitching 17.

Stays 18 are placed upon the outside of the fabric 13 and are secured to the top and 30 bottom members by means of rivets 19 and 20. These stays are covered preferably by means of leather strips 21 which are sewed to the fabric of the bag.

The rawhide forming the top and bottom 35 members is first steamed and treated for several hours until it is very soft and pliable, in which condition it is formed as shown and retained in this position until it has be-

come quite dry. By that time it has become set and rigid and forms a stiff solid member 40 top and bottom to which the stays 18 are united. This prevents the usual break-down at this point where the stiff wire stay is united to the leather as is commonly done.

The rawhide ends also resist water un- 45 der all ordinary conditions and are not materially affected by the conditions to which a golf bag is likely to be subjected.

While I have shown and described certain 50 embodiments of my invention, it is understood that it is capable of many modifications. Changes therefore in the construction and arrangement may be made without departing from the spirit and scope of the 55 invention as disclosed in the appended claim, in which it is my intention to claim all novelty inherent in my invention as broadly as possible in view of the prior art.

What I regard as new and desire to secure by Letters Patent, is—

In a golf bag in combination, a top comprising a ring, a strip of rawhide doubled about said ring, flexible body material secured between the portions of said rawhide, stays secured to said body portion and ex- 65 tending between the portions of said raw- hide, rivets passed through said rawhide and said stays, a bottom comprising an end mem- ber having a downward turned annular flange, a strip of rawhide formed in an an- nular channel enclosing said flange, said body material extending between the annular flange and rawhide, and rivets passed through the rawhide and engaging said stays and said body material.

JAMES S. WHITE.
